UNITED STATES PATENT OFFICE.

ARTHUR BAHNMAYER, OF MANNHEIM, GERMANY.

INDICATOR AND RECORDER FOR HIGH PRESSURE.

Application filed February 28, 1923. Serial No. 621,939.

To all whom it may concern:

Be it known that I, ARTHUR BAHNMAYER, a citizen of the German Empire, residing at Mannheim, Germany, have invented certain 5 new and useful Improvements in Indicators and Recorders for High Pressure, of which the following is a specification.

My invention relates to a novel and very advantageously constructed indicator for 10 high pressures, for the recording and measuring of pressures in riveting, pressing and drawing operations.

It is well known that presses, as riveting-machines, drawing-presses, block-presses and 15 the like, which are operated by press-fluid or press-air frequently work in a way that the same working-pressure operates upon active piston-faces (steps) of different sizes. This causes operating pressures of different power 20 on the work-piece or on the tool, e. g. on the punch of a riveting-machine. A further variation or graduation of the operating pressures results from the variation of the tension of the driving-medium; the latter 25 may for instance be raised from n atmospheres to $2n$ atmospheres.

My invention has for its object an indicator which surely and positively operates and indicates at the highest pressures 30 happening in doing the aforementioned work without having the indicator submitted to any material change in its ordinary construction and shape. Furthermore my invention aims to simple means for automatically 35 indicating such operative pressures to be used in the riveting-machines or the like as reliable and economical for the work at hand e. g. the diameters of the rivets or the scales of the sheet-metals.

In order to make myself quite clear to facilitate the understanding of my invention I refer to the accompanying drawing, in 40 which the new device is shown as an instance only, partly in section, partly in plan view together with a hydraulic riveting-machine 45 and its accumulator, the two latter devices on an essentially smaller scale than the former.

What is said and explained herein about 50 riveting-machines applies also to any other press-device, when a rational treatment of the work-piece to be dressed, the control of the proceeding and the workmen themselves are desired.

In the drawing, C designates a riveting- 55 machine, which in this instance works with

a two-stepped piston I and II. If you cause the working-medium (the operating water and so forth) to act upon both piston-steps you get a third step III. If the normal water-pressure in this instance amounts to n kilograms per square centimeter the compression of three different grades can be exercised on the die c of the riveting-machine C. 60 65

As shown in the drawings the pump A acts by means of the pressing tubes in the well known way on the accumulator B. The accumulator B feeds in the likewise well known way by means of the tubes 3 and 4 70 the riveting-machine C. According to the rivet diameter either step I or step II, or both steps together as step III, will be operated.

There are tubes a' and b' leading from the 75 compression-spaces I and II respectively of the riveting-machine C to an indicator D, the feature of which is its being constructed as a differential indicator. The riveting machine is provided with two valves 27 and 28; 80 for throwing into operation the step I the valve 28 is shut off and the valve 27 opened, for setting into operation the step II valve 27 is closed and valve 28 opened. The step III comes into operation by opening both 85 the valves 27 and 28. The same pressure which is acting upon the different steps comes into operation within the corresponding tubes and spaces which are in communication with their corresponding steps. 90

Every time when a step of the riveting-machine receives a pressure the water-pressure also operates at the same time on the two differential pistons k^1 and k^2 . The two pistons k^1 and k^2 are fixed to a piston-rod 95 consisting of two parts k^4 , k^5 articulated by a hinge k^3 . The stroke of the differential pistons k^1 , k^2 is marked on the drum G by the writing-lever f^1 . The areas of these two indicator pistons are such that a comparatively small differential pressure is produced in an upward direction, as the piston of the larger area is toward the upper end of the indicator cylinder D, thus allowing the operation of the writing lever f^1 by the usual 100 lever-arrangement 5, 6 and an indicator spring F having the usual or normal resiliency force, nevertheless the highest pressures are upheld within the riveting-machine.

It is a further feature of my invention to 110 have the indicator drum adjusted in accordance with the step of the riveting machine

just in operation. For this purpose the drum G is fastened to a piston rod e^1 carrying three adjusting pistons 1', 2', 3'; these pistons rigidly connected to the rod e^1 , are of increasing diameters and adapted to slide within the corresponding driving cylinders d^1 , d^2 and E. The cylinders d^1 and E are in communication respectively with the steps II and I of the machine by tubes a'' and b'' .

10 At its upper end the drum G is in connection with a piston rod r , to which is fixed a counter-piston H, sliding within a cylinder h^1 in communication by 4' with the accumulator B.

15 The drum G comprises three recording sections in accordance with the three operative steps I, II and III of the riveting machine, the first section extending between the zero-line and the 50 tons-line, the second section 20 between the 50 tons-line and the 100 tons-line, whereas the third section lies between the 100 tons-line and the 150 tons-line. As the writing-lever f^1 extends over one section of the drum G only, the latter has to be 25 adjusted in such a way, that if the step I of the machine is in operation the writing pencil of the lever f^1 is standing upon the zero-line. Owing to the fact that the tube b'' is shut off by the piston 3' and the cylinder 30 h^1 is fed with pressure fluid the counter-piston H is enabled to hold the drum G in its uppermost position as shown by the drawing. If the step I of the machine is shut off and the step II is fed with pressure fluid, the 35 latter flows by the tube a'' into the cylinder d^1 and forces the rod e' together with the drum G downwardly; of course it is understood that the water also passes between the 40 upper face of the piston 2' and the shoulder d^2 ; the downward movement is cut off if the piston 1' closes the tube a'' ; in this case the 45 50 tons-line coincides with the pencil of the writing lever f^1 . Should there be fed both the steps I and II with pressure water, the latter flows by the tube b'' into the cylinder E, containing the largest piston 3' and accordingly throws the drum G into its lowest 50 position, whereby the pencil of the writing lever automatically coincides with the 100 tons-line.

A further important feature of my invention forms the means to automatically control the work when done and to prevent the work-piece from receiving unreliable working pressures. For this the following arrangement is provided: a stopping arm a^4 , carrying an insulated contact piece 8, is movably mounted on a guiding rod q by means of a sleeve L; to the latter is attached a rack 60 11, which engages with pinions 12, 13; on the axis 14 of the latter is keyed a cam wheel K having in accordance with the three steps 65 of the riveting machine three teeth 16 of different length and adapted to cooperate with corresponding teeth 17 of a rotatable sector

7, having a pointer 19, to be adjusted on a graduated arc 20, and a curved arm b^3 adapted to cooperate with a fixed stop wall 21 thus forming a controlling jaw of changeable width intended to receive the rivets to be 70 worked upon, such as 22, serving as a controlling caliber. The arc 20 comprises the three sections 23, 24 and 25, as required by the three steps I, II, III. According to the 75 diameter of the controlling rivet 22 the said jaw will assume a corresponding width and therefore the sector J performs a rotative motion, which is transmitted by means of the points 16, 17, the pinions 13, 12 to the rack 11 whereby the stopping arm a^4 is lifted to 80 the prescribed height; as in the drawing the pointer 19 points to the end of the first section-scale of the graduated arc 23 the stopping arm coincides with the 50 tons-line of the drum G. Should there be produced a 85 higher pressure by the riveting machine, the contact 25 of the writing lever strikes on the contact 8 whereby a current is closed over a battery 26 to an alarm bell f^2 which sounds and gives a signal to the workman. To obtain the second step the corresponding teeth 17 and 16 must disengage from each other, thus permitting of the cam wheel K and the 90 gear wheels 13 and 12 a corresponding backward rotation till the following points 16, 17 engage with each other. Due to this backward movement the stopping arm a^4 is allowed to descend on its initial position; a tension spring 26 supports the downward 95 movement of the arm a^4 . Now the controlling jaw b^3 , 21 is adapted to receive a larger rivet.

Having now particularly described and ascertained the nature of my said invention and in what manner the same is to be performed, I declare that what I claim is:

1. An arrangement for recording and measuring high pressures, in riveting-, pressing- and drawing works, comprising in combination differential pistons operated by the working-fluid, differential-cylinders receiving the said differential pistons, a piston rod carrying the said differential pistons, a writing-lever operated by the said piston rod, an indicator spring preferably of the usual structure, influencing the writing-lever, a writing-drum adapted to be moved in axial direction and cooperating with the said writing lever, an adjusting rod and adjusting pistons thereon of different diameters for carrying the said drum, governing cylinders, receiving the said adjusting pistons and fluid conducting tubes for bringing into communication the differential-cylinders and the governing-cylinders with the working-machine substantially as 115 described.

2. In the arrangement for recording and measuring high pressures a device for indicating and controlling the fluid-pressure

as required, comprising a movable arm and a stop-wall, forming a jaw of changeable width, a rotatable sector carrying said movable arm, a pointer and driving organs arranged at said sector, gearing wheels co-operating with the said sector-organs, a stopping arm slidably mounted and adapted to be operated by the said gear wheels and carrying an electrical contact, a writing lever, cooperating with the said stopping arm and contact at certain positions and means for producing a signal in case the writing lever and stopping arm interfere with each other, substantially as described.

15 3. In the arrangement for recording and measuring high pressures in riveting and the like machines, an indicator comprising a plurality of differential pistons, a corresponding number of differential cylinders, 20 receiving the said differential pistons, piston rod-sections carrying the corresponding differential pistons and being articulated with each other, fluid pressure tubes putting into communication the pressure spaces of 25 the riveting and the like machine with the differential cylinders, a writing lever, a lever-arrangement for guiding the writing lever, an indicator spring preferably of the usual art, cooperating with the writing lever 30 and an adjustable drum for carrying the indicator strip substantially as described.

4. In the arrangement for recording and measuring high pressures in combination with a pressure source and a machine for riveting and the like, a movable drum, an adjusting-rod to which the said drum is fastened, differential adjusting pistons, driving cylinders for receiving the said differential adjusting pistons, fluid tubes putting into communication the machine and the pressure source with the said driving cylinders, the adjusting pistons being adapted to shut off single tubes at certain positions of the adjusting pistons and the drum respectively.

45 5. In the arrangement for recording and measuring high pressures in riveting and the

like machines, comprising in combination a diagram-strip, a carrier for the latter, differential adjusting pistons and driving cylinders for the adjustment of the said strip-carrier, means for conducting the pressure-fluid from the working machine to the said adjusting cylinders, a controlling jaw of changeable width adapted to cooperate with the working-piece as a rivet and the like, a movable stopping arm and a writing-lever cooperating for producing a signal in case the prescribed working pressure is surpassed and means for transmitting the movement of the movable jaw to the stopping arm.

6. In the indicator arrangement as herein before described, a controlling jaw consisting of a movable and a fixed part and adapted to be adjusted in accordance with the scale of the working-piece (rivet, sheet or the like) to be dressed, a pointer in connection with the movable part of the controlling jaw, to show the working pressure as reliable for the work to be done, a stopping arm co-operating with the writing lever of the indicator and a transmitting gear for transmitting the movement of the said movable part of the jaw to the said stopping arm.

7. In the indicator-arrangement as herein before described, a controlling jaw comprising a movable and a fixed part and adapted to receive the working-piece (rivet, sheet or the like) to be dressed, a stopping arm co-operating with the writing-organ of the indicator, means for transmitting the movement of the movable part of the controlling jaw to the stopping arm, and a signaling device alarming the workman, if the operative fluid pressure is surpassed, by the co-operation of the stopping arm with the writing lever.

In testimony whereof I affix my signature in presence of two witnesses.
